(57) **CLAIM**

The ornamental design for a robotic vacuum cleaner for vehicles as shown and described.

DESCRIPTION

FIG. 1 is a front, right side, perspective view of a robotic vacuum cleaner for vehicles showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front, right side, perspective view a robotic vacuum cleaner for vehicles lowered in an alternate configuration thereof; and,

FIG. 9 is a front, left side, perspective view showing the state in which the robotic vacuum cleaner is installed in the vehicle.

The broken lines in FIG. 7 depict portions of the robotic vacuum cleaner for vehicles that form no part of the claimed design. The broken line showing in FIG. 9 is for the purpose of illustrating environmental structure and forms no part of the claimed design.
